CLAIM

The ornamental design for a portable electronic device, as shown and described.

DESCRIPTION

FIG. 1 is a perspective view of a first embodiment of the portable electronic device of the present invention.

FIG. 2 is a front view of the embodiment of FIG. 1.

FIG. 3 is a bottom view of the embodiment of FIG. 1.

FIG. 4 is a rear view of the embodiment of FIG. 1.

FIG. 5 is a right view of the embodiment of FIG. 1.

FIG. 6 is a left view of the embodiment of FIG. 1.

FIG. 7 is a top view of the embodiment of FIG. 1.

FIG. 8 is a perspective view of a second embodiment of the portable electronic device of the present invention.

FIG. 9 is a front view of the embodiment of FIG. 8.

FIG. 10 is a bottom view of the embodiment of FIG. 8.

FIG. 11 is a rear view of the embodiment of FIG. 8.

FIG. 12 is a right view of the embodiment of FIG. 8.

FIG. 13 is a left view of the embodiment of FIG. 8; and,

FIG. 14 is a top view of the embodiment of FIG. 8.

(Continued)

The design is the overall configuration, shape, ornamentation and pattern of the portable electronic device as shown in the drawings in which.
